LAMP HOOD FOR ELECTRIC LAMPS

Filed July 21, 1926

Inventor:
William L. Laib
By Harry J. Donner
Atty:

UNITED STATES PATENT OFFICE

WILLIAM L. LAIB, OF CHICAGO, ILLINOIS

LAMP HOOD FOR ELECTRIC LAMPS

Application filed July 21, 1926. Serial No. 123,980.

This invention relates to lamp hoods which are adapted to be used for enclosing or covering electric lamps or lamp bulbs, such, for example, as incandescent electric lamps or 5 lamp bulbs for lighting electric signs, or for similar or other purposes.

The principal object of my invention is to provide a simple, economical and efficient lamp hood for electric lamps, and more particularly, to provide a lamp hood comprising a cup-shaped member adapted to form the closed end of a lamp hood and having an annular peripheral rim or margin adapted to encircle a lamp bulb, and connecting and supporting means, such, for example, as a tapered annular sleeve or hood member adapted to be secured in supporting engagement with such cup-shaped hood member and in position to encircle or engage such lamp bulb, 15 whereby the desired lighting and color effects may be obtained and such lamp hoods may be mounted and effectually secured upon such lamps and removed and replaced with facility whether the lamps be located indoors or out-of-doors where the hoods are subjected to the action of the wind and to varying weather conditions and are frequently in positions which are difficult of access.

Other and further objects of the invention will appear from the following description and claims, and from an inspection of the accompanying drawings, which are made a part hereof.

The invention consists in the features, combinations of elements, details of construction and arrangement of parts herein described and claimed.

In the accompanying drawings—

Figure 1 is a view in side elevation of an improved lamp hood constructed in accordance with my invention, showing the same in position upon an electric lamp which is mounted upon and adapted to form a part of an electric sign, and which lamp and hood are adapted to be used either for lighting flasher signs or for other electric lighting purposes;

Fig. 2 is an end view of the lamp hood and lamp shown in Fig. 1;

Fig. 3 is a central longitudinal sectional view of the lamp hood shown in Fig. 1, taken on line 3—3 of Fig. 1, and showing the electric lamp and lamp bulb in side elevation, with the hood mounted thereon;

Fig. 4 is a detail view in side elevation of a cup-shaped or hemispheroidal cap or end hood member, such as is shown in Fig. 3;

Fig. 5 is a view in detail of the inner or peripherally flanged and notched rim or margin of the cup-shaped cap or end member shown in Fig. 1;

Fig. 6 is a detail view in side elevation of a tapered annular sleeve member, partly in section and with a part broken away, and showing an opaque reflector surface, said sleeve member being a modification which may be made of either metal or glass.

In Figs. 1 and 2 a lamp hood constructed in accordance with my invention is shown mounted upon and adapted to enclose an ordinary incandescent electric lamp bulb 3 which is mounted in a lamp socket 4, said socket being mounted upon a suitable support 2, which may be a sign board or lamp supporting plate of an electric sign having any desired number of electric lamps provided with such lamp hoods; or the electric lamp or lamps in connection with which my improved lamp hoods are to be used may be of any desired ordinary and well known or suitable form, and may be mounted in any desired manner upon any suitable support or structure.

In constructing an improved lamp hood for electric lamps, in accordance with my invention, I provide a hollow cup-shaped end hood member 5 which is, by preference hemispheroidal in form, and made of glass which may be of any desired color or shade or combination of colors, and may be transparent or translucent, or in part transparent and in part translucent, or opaque, or may be made of any suitable material. The hollow spheroidal or cup-shaped hood member 5 is adapted to form the closed end of a lamp hood constructed in accordance with my invention, and has an annular, preferably notched or stepped peripheral margin or rim 6 provided with alternate notches or recessed

80

85

90

95

100

5 marginal portions 7 and protuberant marginal tongue or shoulder portions 8 which project or extend endwise beyond the adjacent notched or recessed peripheral marginal portions 7. The extended peripheral tongue or shoulder portions 8 are, by preference, each provided with an integral peripherally protruding securing flange or shoulder 9 which is provided with a circumferential recess 10
10 on the back side of the flange, which recess is adapted to receive a curved or annular flexible, preferably resilient, securing member or connecting wire 11 which may be formed of spring metal or other suitable material.
15

I also provide an annular tapered open end member 12 which is, by preference in the form of a truncated cone or tapered sleeve, formed of glass and open at both ends, the
20 relatively small open end 13 being adapted to encircle the neck of a lamp or lamp bulb 3 and to form the open end and elongated or tapered neck portion of the hood, and the relatively large end or peripheral margin or
25 rim 14 being, by preference, stepped or provided with alternate notches or recessed marginal portions 15 and extended marginal tongue or shoulder portions 16 which are between and project beyond said recessed marginal portions 15 endwise of the hood in position to fit into and in abutting engagement with corresponding adjacent recesses or recessed marginal portions 7 of the hemispheroidal hood member 5. The notched or recessed peripheral marginal portions 15 of the open end hood member 12 are adapted to receive and engage corresponding adjacent extended marginal tongues or shoulder portions 8 of the cup-shaped hemispheroidal hood member 5. And the extended peripheral marginal tongue or shoulder portions 16 on the relatively large peripheral margin or rim 14 of the open hood member 12 are each, by preference, provided with an integral peripherally protruding securing flange or shoulder 17, said flange having a transverse circumferential recess 18 located on the back side of the flange and adapted to receive the curved or annular circumferential resilient connecting wire 11, which is adapted to partly or wholly encircle the hood and to extend between the flanges 17 and 9, so as to securely connect and hold the peripheral margins 14 and 6 of the hood members
50 12 and 5 in abutting interlapping interlocking engagement with each other and thereby securely connect the hood members 5 and 12 and hold them, by preference detachably, upon and in position to enclose or encircle a lamp bulb of an electric lamp in connection with which the lamp hood thus formed is to be used.
60

65 By making the curved or annular connecting wire 11 of resilient material, such, for example, as spring steel, and of sufficient

length to completely or almost completely encircle the lamp hood, it may be readily snapped in place, so as to be held at a tension in position to pass between the protruding connecting flanges or shoulders 9 and 17, and securely connect and hold the hood members 5 and 12 together upon and in position to enclose the lamp bulb. The extreme ends of the connecting wire 11 may be turned outward, to afford a convenient means for enabling the operator to hold and spread the connecting wire and snap it in its proper operative position around the peripheral margins or rims of the hood members 5 and 12 and between the connecting flanges or shoulders 9 and 17. The ends of the connecting wire may of course be connected together if desired by being bent or hooked in engagement with each other.
70
75
80

The hood members 5 and 12 are, in the preferred form of my improved lamp hood, made of glass; and they may be both of the same color or of different colors. And either one or the other may be transparent or translucent and connected and used in connection with a mating hood member which may be either transparent, translucent or opaque, or in connection with one having a reflector surface. And the reflector surface may be on the member 12 as shown in Fig. 6, in which the member 12 is formed of metal or opaque material coated with porcelain or painted to form a bright reflector surface 19, or may be on the cup-shaped hood member 5, the other hood member 12 being of glass or other transparent or translucent material, but preferably glass.

I claim:

1. A lamp hood comprising a cup-shaped glass hood member forming a closed end of a lamp hood, and having an annular peripheral margin adapted to encircle a lamp bulb, a tapered annular sleeve-shaped bulb-encircling hood member having an annular peripheral margin adapted to engage said cup-shaped hood member, said hood members having alternately disposed marginal recesses in and shoulders on their engaged annular peripheral margins, each of said shoulders being located between and in engagement with a plurality of adjacent shoulders on the opposite hood member, and a flexible connecting element extending circumferentially of the hood and in securing engagement with marginal shoulders on both of said hood members, for connecting said hood members and holding the same in operative position with respect to the lamp bulb.
110
115
120

2. In a lamp hood, the combination of a cup-shaped hood member having an annular peripheral margin adapted to encircle a lamp bulb, said margin having alternate recesses and extended marginal shoulder portions, an annular sleeve-shaped hood member adapted to form an open end of the hood and having
125
130

integral marginal shoulder portions adapted to extend into the marginal recesses and between and in engagement with the sides of adjacent marginal shoulders of said cup-shaped hood member, and connecting means in engagement with the marginal shoulder portions of both of said hood members and adapted to secure the latter in engagement with each other.

3. In a lamp hood, the combination of a cup-shaped glass hood adapted to fit the end of an incandescent lamp bulb and having an annular end margin adapted to encircle such bulb, a plurality of end shoulders spaced apart circumferentially on said annular end margin and projecting endwise of the hood and having marginal recesses between said shoulders, an annular tapered sleeve-shaped glass hood member adapted to encircle the neck of the lamp bulb, a plurality of end shoulders on the annular end margin of said sleeve-shaped hood member and projecting endwise between and in abutting engagement with the side margins of adjacent end shoulders on said cup-shaped hood member, the end of each of said shoulders being in abutting engagement with the bottom of a corresponding recess between said engaged shoulders on the opposed hood member, and resilient connected means encircling the engaged shoulders of both of said hood members and adapted to hold each of said shoulders in position between and in abutting engagement with the side margins of adjacent shoulders on the opposed hood member, for connecting said hood members and engaged shoulders in abutting circumferentially immovable relation to each other on the lamp bulb.

4. In a lamp hood, the combination of a cup-shaped glass hood member adapted to fit the end of an incandescent lamp bulb and having an annular bulb-encircling end margin, a plurality of end shoulders spaced apart circumferentially on said annular end margin and projecting endwise of the hood and having marginal recesses between said shoulders, an annular tapered sleeve-shaped glass hood member adapted to encircle the neck of the lamp bulb, a plurality of integral end shoulders spaced apart circumferentially on said annular end margin of said sleeve-shaped hood member and each projecting endwise between and in abutting engagement with the side margins of a plurality of said end shoulders on said cup-shaped hood member, the end of each of said shoulders being in abutting engagement with the bottom of a corresponding recess in the opposed hood member, outwardly projecting peripheral flanges on the shoulders of each of said hood members, and a resilient metallic connecting member encircling the engaged flanged shoulders and extending between and in securing engagement with the outwardly projecting peripheral flanges on said shoulders of both

of said shouldered hood members, for securing said shoulders and hood members in circumferentially immovable relation to each other on the lamp bulb.

Signed at Chicago, in the county of Cook 70 and State of Illinois, this 6th day of July, 1926.

WILLIAM L. LAIB.
